US00D755220S

(12) **United States Design Patent**
Yu et al.

(10) **Patent No.:** **US D755,220 S**
(45) **Date of Patent:** **** May 3, 2016**

(54) **DISPLAY SCREEN OR PORTION THEREOF
WITH GRAPHICAL USER INTERFACE**

(71) Applicant: **Samsung Electronics Co., Ltd.**,
Suwon-si, Gyeonggi-do (KR)

(72) Inventors: **Seock Hyun Yu**, Seoul (KR); **June-Seok Kim**, Seoul (KR); **Ji young Moon**, Seoul (KR)

(73) Assignee: **SAMSUNG ELECTRONICS CO., LTD. (KR)**

(**) Term: **14 Years**

(21) Appl. No.: **29/495,672**

(22) Filed: **Jul. 2, 2014**

(30) **Foreign Application Priority Data**

Jan. 3, 2014 (KR) 30-2014-0000465

(51) **LOC (10) Cl.** **14-04**

(52) **U.S. Cl.**

USPC **D14/486**; D14/488

(58) **Field of Classification Search**

USPC D14/485-495; D20/11, 27, 39

CPC .. G06F 3/048-3/4897; G06F 17/30-17/30997

(57) **CLAIM**

We claim, the ornamental design for a display screen or portion thereof with graphical user interface, as shown and described.

DESCRIPTION

The FIGURE is a front view of a display screen or portion thereof with graphical user interface showing our new design. The broken lines illustrate the display screen or portion thereof, and illustrate portions of the graphical user interface, and form no part of the claimed design.

1 Claim, 1 Drawing Sheet
